[57] CLAIM

The ornamental design for a game piece or similar, as shown.

DESCRIPTION

FIG. 1 is a perspective view of a game piece or similar showing my new design;

FIG. 2 is a top plan view thereof;

FIG. 3 is a bottom plan view thereof; and

FIG. 4 is an elevational view thereof.

The broken lines showing of support in FIG. 1 is for illustrative purpose only and forms no part of the claim.

FIG. 1

FIG. 2

FIG. 3

FIG. 4
